Application December 15, 1950, Serial No. 200,971

2 Claims. (Cl. 261—69)

1

This invention relates to new and useful improvements in valves.

The invention is particularly concerned with valves having diaphragms functioning as valve members, and with the utilization of such valves, as in water injection devices for internal combustion engines.

One object of the invention is to provide a novel valve having an annular seat adapted to be engaged by a flexible member, such as a diaphragm, and having flow spaces interior and exterior of the annular seat.

An important object of the invention is to provide an improved valve having a flexible valve member, such as a diaphragm, and responsive to an increasing pressure to supply increasing quantities of a fluid to the zone of increasing pressure.

A particular object of the invention is to provide an improved valve which may be connected to the intake of an internal combustion engine and which is responsive to a decreasing suction in said intake to open and supply through suction increasing quantities of a fluid to the intake as the suction in the latter decreases.

A further object of the invention is to provide an improved valve of the character described having areas adapted to be exposed to pressures of different values, said areas being subject to variation to alter the performance of the valve.

Yet another object of the invention is to provide an improved valve of the character described having a flexible valve member, such as a diaphragm, and which may have a spring employed to bias the valve member, or utilize a zone of fluid pressure to bias the member, or employ both the zone and the spring for biasing.

One of the objects of the invention is to provide an improved water injection device for internal combustion engines which is simple and inexpensive to manufacture, and yet which is extremely efficient and reliable in operation and requires a minimum of maintenance and servicing.

Another object of the invention is to provide an improved device of the character described having a water reservoir and means for maintaining said reservoir at a substantially constant level, the device having a metering type diaphragm valve normally held closed by the partial vacuum existent in an engine intake manifold, but progressively opening as the manifold pressure approaches a maximum to permit increasing quantities of a water mixture to be metered into the engine carburetor air stream to enhance the performance of the engine.

2

Yet another object of the invention is to provide an improved device of the character described having an improved and novel arrangement for the withdrawal of water from the water reservoir, and also having an improved and novel air vent arrangement.

A construction designed to carry out the invention will be hereinafter described together with other features of the invention.

10 The invention will be more readily understood from a reading of the specification and by reference to the accompanying drawings, wherein examples of the invention are shown, and wherein:

15 Fig. 1 is a side elevation of a valve constructed in accordance with this invention and connected to an engine intake stack,

Fig. 2 is a vertical, sectional view of the valve, showing the same completely closed,

20 Figs. 3, 4, and 5 are views similar to Fig. 2 and illustrating the progressive opening of the valve,

Fig. 6 is a horizontal, cross-sectional view taken on the line 6—6 of Fig. 3,

Fig. 7 is a view similar to Fig. 2 and showing a 25 modification of the valve,

Fig. 8 is a side elevation, partially broken away, of a water injection device employing a valve constructed in accordance with this invention, and showing the device connected to an engine intake stack,

30 Figs. 9 and 10 are horizontal, cross-sectional views taken upon the respective lines of Fig. 8,

Fig. 11 is an enlarged perspective view of the diaphragm spring plunger, and

35 Fig. 12 is a graph illustrating the operation of this invention.

This application is a continuation-in-part of my copending application, Serial No. 682,019, filed July 8, 1946, now Patent No. 2,597,335, issued May 20, 1952, which in turn, is a continuation-in-part of my co-pending application, Serial No. 625,069, filed October 27, 1945, now abandoned.

Proceeding first with a description of an actual installation or utilization of the valve with which this invention is concerned, will provide a more adequate understanding of the function and advantages of the valve. It is to be noted that in my co-pending application, Serial No. 682,019, filed July 8, 1946, there is shown the utilization of the valve for fuel mixture enriching means. In the present application, there is shown in Figs. 7 through 11 the employment of the valve in a water injection device.

In the illustration of the water injection device, the numeral 10 designates the intake stack of an internal combustion engine, the intake stack

having the customary choke valve 11 and throttle valve 12. As is customary, fuel is supplied to the venturi 13 of the intake stack through a suitable fitting 14. Normally, the intake stack is suitably connected to the engine intake manifold 15, there being illustrated in the drawing a downdraft type carburetor or intake stack in which air flows downwardly into the engine manifold. Of course, this invention is equally applicable to updraft carburetors in which the air stream and fuel mixture flows upwardly into the engine intake manifold.

In connection with the present invention, a suitable fitting in the form of a ring 16 is connected between the intake stack and the intake manifold, the ring 16 including a laterally extending boss 17 having a passage 18 communicating through the wall of the ring 16 with the interior of the intake stack. A water mixture is supplied through the passage 18 to the air and fuel mixture stream flowing into the engine in accordance with the purposes of this invention.

Water injection for internal combustion engines is well known and involves supplying water vapor or a stream of water mist or droplets to the intake manifold of an internal combustion engine. Within the engine, some cooling is effected by the water or water vapor, and apparently, there is a dissociation and a recombination of the molecules of the water to enhance and improve the performance of the engine. It is known that additional power may be obtained from an engine by this method, and that fuels of lower octane rating may be employed. These bursts of power, or apparent increases of the fuel octane rating, are needed only when the engine is under a heavy load, and hence, it is desirable to supply the water or water vapor only at such times. The present invention includes an extremely simple and efficient device for supplying the water or water vapor only at such times when the manifold pressure approaches a maximum value, these being the times in which the engine is under its heaviest load.

While the term "water" is used herein to designate the fluid supplied to the engine intake manifold, it is to be understood that this term is being used only in its generic sense. In actuality, the fluid mixtures supplied by water injection devices may include water, alcohol, tetraethyl lead, and various other chemical additives. Indeed, the fluid may consist predominately of an alcohol, such as an ethyl alcohol, or various other organic or inorganic fluids or materials. It is not intended or desired that this invention be limited to the use of any particular fluid since it is adapted to supply in metered quantities any fluid or material to an internal combustion engine which will have a beneficial effect upon the performance of the engine when admixed with the air fuel stream.

The metering device includes a central body 19 of substantially cylindrical configuration, the upper portion of the body 19 being reduced in diameter to form an annular upwardly directed shoulder 20 intermediate the ends of said body, and being further reduced in diameter to form a second shoulder 21 adjacent the extreme upper end of the body.

A bowl or housing 21' is provided with an aperture 22 in its bottom and adjacent its central axis, the aperture 22 receiving the reduced upper end of the body 19, and the shoulder 20 engaging the underside of the bowl 21'. The body may be soldered or otherwise suitably secured to the bowl to form a liquidtight joint.

A flat cover plate 23 is received upon the open upper end of the bowl 21' and is secured thereto by machine screws 24 extending through the edges of the cover plate into a marginal flange 25 turned outwardly upon the upper extremity of the bowl. The central portion of the cover plate 23 is dished downwardly to form a sump or chamber 26, the extreme upper end of the body 19 extending into the bottom of the chamber 26 through an opening 27 cut in the dished portion of the cover plate. The portion of the cover plate immediately adjacent the opening 27 engages the seat 21 so that the bowl and cover plate cooperate to form an annular chamber or water reservoir 28 surrounding the reduced upper portion of the body 19. A hollow circular float 29 is disposed within the reservoir 28 and is hinged upon a pin 30 extending transversely of said reservoir. The float 29 controls the action of a valve 31 so that fluid may flow into the reservoir from a suitable storage tank 32 and a hose 33 connecting said tank and the valve 31. This arrangement is conventional and serves merely to maintain within the reservoir 28 a body of water or other fluid for enhancing the performance of an internal combustion engine, said fluid being maintained by means of the float and the valve at a substantially constant level L.

An annular groove 34 is cut in the reduced upper portion of the body 19 immediately above the shoulder 20 so as to be disposed within the lower portion of the water reservoir 28. A bore 35 extends longitudinally of the body 19 intersecting the groove 34 and extending to the upper end of the body into the chamber 26. The lower portion of the bore is enlarged and receives a screw-threaded metering valve 36 having its head 37 recessed or countersunk in the lower end of the body 19 and being adjustable within the bore 35 to vary the passage or flow space between the groove 34 and said bore 35. A second annular groove 38 is cut in the upper portion of the body 19 immediately below the shoulder 21 and above the normal liquid level L. A small air vent 39 extends from the groove 38 into the bore 35.

Within the chamber 26, an upstanding sleeve 40 is provided, said sleeve being formed integrally with and extending upwardly from the upper end of the body 19, and having its open upper end terminating in a horizontal plane substantially flush with the upper surface of the cover plate 23. A circular diaphragm 41 overlies the chamber 26 and the open upper end of the sleeve 40, a suitable apertured retaining plate 42 engaging the marginal portion of the diaphragm 41 and securing the same to the cover plate 23. As shown in Fig. 8, the diaphragm 41 extends entirely across the upper portion of the chamber 26 and encloses the same.

A finned diaphragm plunger 43 is disposed within the bore of the sleeve 40 and engages the underside of the diaphragm 41. A suitable coil spring 44 constantly urges the plunger 43 upwardly against the diaphragm, and a reduced conduit or passage 45 extends downwardly from the bore of the sleeve into the lower portion of the body 19. An enlarged screw-threaded opening 46 extends laterally into the lower end of the body 19 and communicates with the passage 45, while a suitable pipe 47 is connected between the opening 46 and the opening 18 of the boss 17 for conducting the water or other fluid from the metering device to the engine intake stack.

In the operation of the device, water or other fluid flows from the storage tank 32 through

the hose 33 and the valve 31 into the chamber 28 until it has built up to the level L. At this point, the float 29 has been raised sufficiently to close the valve 31 and to prevent further flow of fluid. Of course, as fluid is withdrawn from the reservoir 28, additional fluid will enter through the valve 31 by reason of the lowering of the float 29. With water standing at the level L, the groove 34 is completely submerged, and water may readily pass thereto through a cylindrical strainer or screen 48 which encompasses the entire upper portion of the body 19. Of course, the water will rise within the passage 35 until it is at the same level as the water surrounding the upper portion of the body 19, but there will be no tendency for the water to rise further through a siphoning or condensation action by reason of the air vent 39 which tends to equalize pressures within and without the passage 35. When the engine to which the device is connected is not in operation, the spring 44 will function to force the diaphragm 41 upwardly from engagement with the upper open end of the sleeve 40, and there will be full communication between the passage 35, through the bore of the sleeve 40 and the passage 45, and the conduit 47, to the interior of the intake stack 10. As soon, however, as the engine is started, a reduced pressure is exerted within the engine intake stack due to the restriction of the throttle valve, and this reduced pressure will draw the diaphragm 41 downwardly onto the sleeve 40, compressing the spring 48 and closing off the path of communication to the engine intake stack from the passage 35. During normal operation of the engine, the device will remain in this condition, and will not commence its metering function until such time as the engine approaches a heavy loading condition. As is well known, the throttle valve of an engine which is heavily loaded is at or near its full open position and the manifold pressure in the intake manifold of the engine is at or near its maximum value. In actuality, the absolute manifold pressure of the engine increases as the engine is progressively loaded, or stated in another fashion, the vacuum exerted within the intake manifold decreases as the engine is loaded. The effect of this increasing pressure or decreasing vacuum is to reduce the force holding the diaphragm 41 in engagement with the open upper end of the sleeve 40 until a point is reached at which such force is insufficient to overcome the strength of the spring 44, and the diaphragm commences to move upwardly away from the open upper end of the sleeve 40. The manifold pressure is still below atmospheric pressure at this point, and there will be exerted now through the sleeve 40 a suction or reduced pressure which will be communicated to the chamber 26 and the passage 35. When this occurs, water rises through the passage 35 and is drawn through the sleeve 40 into the intake stack to provide the desirable and beneficent results characteristic of water injection in an internal combustion engine. As the engine load increases and decreases in the maximum loading range, the position of the diaphragm 41 will shift with respect to the sleeve 40 to provide a corresponding increase or decrease in the quantity of water or other fluids supplied through the pipe 47 and to vary or meter the water injection phenomena in accordance with the degree of loading of the engine. As soon as the engine load is reduced below the maximum range, the diaphragm will seat fully upon the sleeve and all water injection will cease. At this point, the

equalizing air vent 39 allows the water within the passage 35 to return to its normal level. It is also to be pointed out that the air vent 39 functions during the metering operation to introduce a small stream of air into the column of fluid within the passage 35 and to aerate or lighten the same so that it is more readily drawn into the bore of the sleeve 40 by the reduced pressure present in the engine intake manifold. Further, the needle valve 36 may be suitably adjusted to regulate and control the flow of fluid from the reservoir 28, but once this needle or metering valve is adjusted for a particular engine, no further manipulation is normally required.

15 The operation of the device is illustrated graphically in Fig. 12 of the drawings, line A representing the decreasing manifold vacuum which is encountered as an engine is loaded progressively from zero to one hundred (100) per cent. 20 As indicated by the line B of the graph, the diaphragm 41 may first unseat from engagement with the sleeve 40 at about a ninety per cent engine loading, and an increasing vacuum will be communicated to the chamber 26 as the engine loading progresses from ninety per cent to one hundred per cent. This is true, because the diaphragm 41 does not move suddenly and completely from engagement with the sleeve 40, but instead, moves gradually therefrom under the force of the spring 44 and as the suction exerted by the engine within the bore of the sleeve 40 decreases. This suction reaches a minimum at one hundred per cent engine loading and the movement of the diaphragm from the sleeve 40 reaches a maximum at the same point. As indicated in the graph, at this point, the manifold vacuum and the vacuum within the chamber 26 are the same.

25 It is apparent from the foregoing that this 30 water metering and injection device functions only in the heavy loading range of an engine, at a time at which increased power or apparently increased octane rating of the fuel is required. It is thus possible to use in an engine a fuel of a 35 lower octane rating than that for which the engine was designed. This is true because it is only under heavy load conditions that the octane rating of an engine fuel becomes extremely critical, and because the present device, under such 40 conditions, supplies an extra boost to the engine and provides an apparent increase in the octane rating of the fuel. As is well known, water injection also provides an increment of power when used in an engine burning fuel of the proper or design 45 octane rating.

45 It is to be noted that the passage 35 is located in the center of the housing or bowl 21, and hence that tilting of the injection device will have no perceptible effect upon the operation of the mechanism since the level within the passage 35 will remain substantially constant at all times. It is further to be noted that the device is extremely 50 simple and rugged in construction and is free of extremely critical or minute passages through 55 which the water or other fluid must flow.

55 Proceeding now with a description of the structure and operation of the valve which forms the principal portion of this invention, the valve includes a bowl 50 having a marginal flange 51 adapted to receive the flange 52 of a domed cover or cap 53. A suitable diaphragm 54 formed of neoprene, butadiene, or any other suitable material is clamped between the flanges 51 and 52 by means of bolts or other fastening means 55 and extends transversely across the enclosure formed

by the interiors of the bowl 50 and the cap 53, dividing said enclosure into an upper chamber C and a lower chamber D. A screw-threaded opening 56 is provided in the cap 53 to furnish communication to and from the chamber C. Similarly, a boss 57 extends laterally from one side wall of the bowl 50 and is provided with an axial passage 58 through which communication is had with the chamber D.

An annular sleeve 59 is formed integrally of the lower wall 60 of the chamber 50 and extends upwardly therefrom axially of the chamber D to the underside of the diaphragm 54. The upper extremity of the sleeve 59 forms a circular or annular valve seat 61 which receives the central portion of the diaphragm 54, the latter functioning in conjunction with the seat 61 as a valve member or valve core. A screw-threaded boss 62 extends downwardly from the bottom wall 60 of the bowl 50 in alignment with the sleeve 59, and an axial passage 63 extends through the boss 62 in communication with a counterbore 64 provided within the sleeve 59. In one form of the invention, a suitable coiled spring 65 is disposed within the counterbore 64 so as to urge the central portion of the diaphragm 54 constantly upward from engagement with the valve seat 61.

In Fig. 1 of the drawings, the valve is shown in a simple connectional relationship with the intake stack 66 of an internal combustion engine, the stack having a Venturi section 67 and a throttle valve 68 downstream of said section. The boss 62 is connected to the intake stack downstream of the throttle valve by a suitable conductor 69, while a pipe 70 leads from the boss 57 to a source of whatever material is to be metered into the intake stack. The upper opening 56 may be exposed to the atmosphere, may be connected into the intake stack 66 upstream of the venturi 67, or may be connected at a point slightly downstream of the throat of the venturi 67, as shown in Fig. 1 by the conductor 71. In each case, the pressure existent within the intake stack or the engine manifold downstream of the throttle valve will be communicated to the counterbore 64, a constant or varying pressure will be communicated to the opening 56, and the pipe 70 will be connected to a source of fluid supply, said source being under a slight or appreciable pressure, but in any event, being at a pressure greater than the maximum pressure existent in the pipe 69 over the range of pressures for which the valve is required to operate. In the case of internal combustion engines, this will be the maximum manifold pressure achieved, but it is obvious that the valve may also be applied in instances in which the pressure exerted through the conductor 69 not only equals the pressure exerted through the pipe 70 but exceeds the same. Of course, in the latter case, flow to and through the conductor 69 will cease.

Although in actual use, the position of the valve shown in Fig. 2 would never be obtained, the same has been included to show clearly the structure of the valve. When the valve is not operating, and the pressures in the chambers C and D are equal, the spring 65 will, of course, push the diaphragm upwardly from and off of the valve seat 61. When, on the other hand, the pressure in the bore 64 is lower than the pressure in the chamber C and the pressure differential is sufficiently high, the diaphragm will be held in engagement with the valve seat 61, but at the same time, the marginal portion of the diaphragm may be bowed or dished downwardly into the cham-

ber D, somewhat in the fashion shown in Fig. 3.

As the pressure differential across or between the chamber C and the bore 64 decreases, the spring 65 will begin to function, and will move the diaphragm slightly upwardly from engagement with the valve seat 61 permitting the initiation of a fluid flow from the passage 58, through the chamber D, and out through the bore 63. As the pressure differential further decreases, the diaphragm moves progressively further from the valve seat 61, as shown in Figs. 4 and 5, increasing the displacement of the diaphragm from the valve seat and increasing the flow from the chamber D into the counterbore 64 and the passage 63. Thus, the diaphragm type valve performs the unique function of responding directly to a decreasing suction (or increasing absolute pressure) to open progressively and meter increasing amounts of a fluid to the suction zone.

When the valve reaches its fully opened position, shown in Fig. 5, the pressure within the passage 63 will be approximately the same as the pressure of the fluid being supplied to the chamber D, there, of course, being a small differential to maintain the flow of fluid. At higher values of vacuum or suction, however, the valve will be partially closed so that the flow to the counterbore 64 from the chamber D is restricted and a smaller quantity of fluid is caused to flow. There is thus provided an extremely simple and inexpensive valve which functions in response to a decreasing suction to give a result normally expected from an increasing suction.

As stated hereinbefore, the valve is subject to considerable variation in that the opening 56 may be exposed to the atmosphere so that the pressure in the chamber C remains constant, it may be connected to the intake stack 66 so that the pressure within the chamber C varies slightly with the velocity of flow through said intake stack but varies only over a relative small range, or it may be connected to the throat of the venturi 67 so as to respond noticeably to the velocity of flow through said venturi and so as to vary the pressure within the chamber C over considerable ranges.

As illustrated in Fig. 7 of the drawings, the spring 65 may be omitted entirely, and the opening 56 connected to the throat of the venturi 67 through the conductor 71 to provide a properly varying pressure in the chamber C to bias the diaphragm 54 in the manner desired. It is known that as the flow of air through a venturi is increased, the pressure at the throat of the venturi is decreased, and hence, the latter arrangement provides for a decreasing pressure within the chamber C as the flow of air through the venturi 67 is increased. The flow of air increases as the throttle valve 68 is opened and therefore as the manifold pressure increases, and it is apparent that there will be a relatively critical point at which the reduced pressure acting upon the upper side of the diaphragm 54 will be sufficient to overcome the suction being applied to that relatively small area of the underside of the diaphragm exposed within the valve seat 61, and at this point that the diaphragm will begin to move from engagement with the seat 61. The movement of the diaphragm or the opening of the valve continues progressively in a metering fashion as the pressure in the chamber C is further reduced and as the suction exerted through the passage 63 is likewise decreased.

A further alternate or modification which may be employed involves the connection of the open-

ing 56 to the throat of the venturi 67 as described hereinbefore, coupled with the simultaneous use of a spring similar to the spring 65 but somewhat less in strength. In this form of the invention, which may be considered as being illustrated in Figs. 1 and 2, the decreasing pressure in chamber C functions in conjunction with the reduced force exerted by the spring 65, and the two together control the movement of the diaphragm 54 as a decreasing suction or vacuum is applied through the passage 63.

It has been found that the characteristic operation of this valve may be varied over a considerable range by variation of the diameter of seat 61 or the area of the diaphragm exposed through said seat to the passage 63. Thus, the ratio of the areas of the diaphragm exposed to the various pressures may be altered at will by enlarging or reducing of the area encompassed by the valve seat 61, and the valve may be caused to function at desired points and to meter flow, after opening, in a desired fashion. If the area encompassed by the valve seat 61 is relatively small as compared to the area exposed to the chamber C, and a relatively heavy spring 65 is employed, the valve will open at a somewhat higher pressure differential than would be the case if a relatively weak spring is employed. Similarly, if the ratio between the exposed areas of the diaphragm is somewhat smaller, the valve will not open until the pressure differential is very small. Hence, it is apparent that the functioning or operation of the valve may be varied to a considerable extent both by varying the area of the diaphragm surface enclosed by the valve seat 61, and by varying the strength or nature of the spring 65.

While the structure and operation of the valve has been described relatively generally, it has been found that the valve is particularly adapted for use in devices carbureting fuel gas to an internal combustion engine. In this application, the pipe 10 may be viewed as being connected to a source of fuel gas under a slight pressure, and that the passage 63 is connected directly or indirectly to the intake manifold of an internal combustion engine. Under these conditions, the absolute pressure within the passage 63 will increase as the throttle valve 68 is opened and as the engine is progressively loaded toward 100% loading. At a point predetermined by the design of the valve and dependent upon the relative areas of the diaphragm exposed to the chamber C and enclosed within the valve seat 61, along with the strength of the spring 65, the diaphragm will begin to move from the valve seat 61 permitting the flow of fuel gas from the chamber D through the passage 63 to the intake manifold of the engine. As an example, such flow might be initiated at a 90% loading of the engine, at a 95% loading, or at any other desired point. As the loading of the engine progresses above the initial point, the manifold pressure will continue to increase (or the suction or vacuum will decrease), so that the spring 65 moves the diaphragm 54 further from the valve seat 61 and provides for a greater flow of fuel gas to the intake manifold, thus further enriching the fuel mixture. This progressive enriching continues

5

until the engine reaches 100% load, at which point the valve is fully opened and maximum enrichment of the fuel mixture is being obtained. As pointed out hereinbefore, the same arrangement may be employed for metering a flow of water into the fuel mixture for the purposes of increasing the power output of the engine.

When the spring 65 is omitted or reduced in strength, and the opening 56 is connected to the throat of the venturi 67, substantially the same results are obtained, the increased suction exerted through the opening 56 by reason of the increasing flow through the venturi functioning to apply an increasing upward thrust to the diaphragm 54 and providing the same valving and metering action.

The foregoing description of the invention is explanatory thereof and various changes in the size, shape and materials, as well as in the details of the illustrated construction may be made, within the scope of the appended claims, without departing from the spirit of the invention.

What I claim and desire to secure by Letters Patent is:

1. In an internal combustion engine fuel supply system of the class wherein a fuel and air mixture is drawn into the engine intake manifold through an engine intake stack having a throttle valve therein, the combination with the intake stack of a metering valve having a housing, means placing the housing in communication with a source of a fuel supplement, a conductor leading from the intake stack between the throttle valve and the intake manifold into the housing and having an opening in the housing, a valve seat surrounding the opening, a flexible disk-like valve closure having one side closing one side of the housing and engaging the valve seat, and means biasing the valve closure away from the valve seat.

2. In an internal combustion engine fuel supply system of the class wherein a fuel and air mixture is drawn into the engine intake manifold through an engine intake stack having a throttle valve therein, the combination with the intake stack of a metering valve having a housing, a pipe leading from the interior of the housing to a fuel supplement supply, a conductor extending into the housing and having an opening exposed therein, a valve seat surrounding the opening, said conductor being in communication with the engine intake manifold, a diaphragm having one side closing one side of the housing and engaging the valve seat, and means biasing the diaphragm away from the valve seat.

55
